(57) **CLAIM**

The ornamental design for an atomizer for electronic cigarette, as shown and described.

DESCRIPTION

FIG. 1 is a front, left, and top perspective view of an atomizer for electronic cigarette showing my new design shown as component 1 removed from the assembly in FIGS. 17-24 for clarity of disclosure;

FIG. 2 is a rear, right, and bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof;

FIG. 8 is a bottom view thereof

FIG. 9 is a front, left, and top perspective view of an atomizer for electronic cigarette showing my new design shown as component 2 removed from the assembly in FIGS. 17-24 for clarity of disclosure;

FIG. 10 is rear, right, and bottom perspective view thereof;

FIG. 11 is a front elevation view thereof;

FIG. 12 is a rear elevation view thereof;

FIG. 13 is a left side view thereof;

FIG. 14 is a right side view thereof;

FIG. 15 is a top view thereof;

FIG. 16 is a bottom view thereof

FIG. 17 is a front, left, and top perspective view of an atomizer for electronic cigarette showing my new design where the component 1 and the component 2 are shown in an assembled state of use;

FIG. 18 is rear, right, and bottom perspective view thereof;

FIG. 19 is a front elevation view thereof;

FIG. 20 is a rear elevation view thereof;

FIG. 21 is a left side view thereof;

FIG. 22 is a right side view thereof;

FIG. 23 is a top view thereof; and,

FIG. 24 is a bottom view thereof.
